UNITED STATES PATENT OFFICE.

JULIAN F. GOODENOW, OF KANSAS CITY, MISSOURI, ASSIGNOR TO GOODENOW-BROOKFIELD KNITTING COMPANY, OF KANSAS CITY, MISSOURI, A CORPORATION OF MISSOURI.

UNDERWEAR.

1,091,504.

Specification of Letters Patent. Patented Mar. 31, 1914.

Application filed March 25, 1913. Serial No. 756,642.

To all whom it may concern:

Be it known that I, JULIAN F. GOODENOW, a citizen of the United States, residing at Kansas City, in the county of Jackson and State of Missouri, have invented certain new and useful Improvements in Underwear; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to underwear, and has for its principal object to provide a full or three-quarter length garment, the lower leg portions of which are adapted to fit snugly over the limbs of a wearer but to yield readily over the knee.

More particularly it is the object of the invention to provide a garment having a body and upper leg portions of woven or non-elastic material adapted to hang loosely on a wearer, and lower leg portions of transversely knit material adapted to cover the wearer's limbs from a point slightly above the knee to the ankle, or slightly thereabove, so as to protect the limbs but allow free movement thereof because of the elastic nature of the knit parts. In accomplishing this object I have provided improved details of garment structure, the preferred form of which is illustrated in the accompanying drawings, wherein the figure is a view of a garment constructed according to my invention, shown on a wearer to illustrate the yieldable effect of the knit portion of the leg.

Referring more in detail to the parts:—1
40 designates the body of the garment, which

is preferably composed of woven non-elastic cloth having leg portions 2 terminating slightly above the knees and adapted to hang loosely on the wearer to afford maximum freedom of movement. Connected with the lower edges of the leg portions 2 are extensions 3, of knit or elastic material, which are arranged transversely to provide longitudinal elasticity, so that the parts covering the knees may yield when the knees are bent.

The lower ends of the transversely knit portions 3 may be provided with anklets 4 to hold the garment snugly about the ankles.

It is apparent that the wearer of a garment, constructed as described, will have complete freedom of movement on account of the looseness of the body and upper leg parts, and the elasticity of the lower leg for knitted parts, while having a covering for the knees and lower limbs, or, in other words, will have the benefit of a full length garment with the comfort of the ordinary knee length suit.

Having thus described my invention, what I claim as new therein, and desire to secure by Letters-Patent, is—

1. An undergarment having a knit knee portion, wherein the wales run transversely of the garment.

2. An undergarment comprising woven body and upper leg portions and knit lower leg portions, wherein the wales run transversely of the garment.

In testimony whereof I affix my signature in presence of two witnesses.

JULIAN F. GOODENOW.
